Primary Examiner—Louis S. Zarfas*Assistant Examiner*—Frank Martinez*Attorney, Agent, or Firm*—Richard C. Litman[57] **CLAIM**

The ornamental design for a portable propane cooking trailer, as shown and described.

DESCRIPTION

FIG. 1 is a perspective view of a portable propane cooking trailer showing my new design in a position of use;

FIG. 2 is a front elevational view thereof;

FIG. 3 is a rear elevational view thereof;

FIG. 4 is a top view thereof; and,

FIG. 5 is a right side elevational view with the left side being a mirror image thereof.

The undisclosed bottom is plain and unornamented.
